AMUSEMENT GAME APPARATUS

Lyndon A. Durant, Chicago, Ill., assignor to
Raymond T. Moloney, Chicago, Ill.

Application October 7, 1937, Serial No. 167,741

6 Claims. (Cl. 273—118)

The invention relates to an amusement game apparatus of the ball rolling type utilizing ball bumped spring contact devices on a game table as obstacle members. These spring bumper devices comprise a pendant cylindrical helical spring disposed on a vertical axis above the game board, said spring constituting a contact element in an electrical circuit including a portion operable with a complementary contact element 5 embedded in the game board. When the spring is bumped by a ball rolling on the board, it is momentarily flexed to close the circuit for energizing a suitable electrical auxiliary for score registering purposes, or the like.

15 It is desirable to use electric lamps in connection with ball rolling game obstacles. In the old pin ball structures such lamps, when carried on the game board, constituted impediments or obstructions to the rolling of the balls. To avoid 20 the game board obstruction just mentioned, designers mounted the lamps on a back board extension of the game cabinet. This was objectionable since the player's attention would be diverted to the back board instead of on the 25 playing board.

Where spring bumpers were used it was difficult for the player to follow the bumpers hit by a ball since there was nothing to indicate to him, except by close observance, which bumper spring 30 was engaged by a ball.

It is thus desirable to associate an electric lamp with each spring bumper so that the player can easily follow the game action, and in such a manner that the lamps will not obstruct the game 35 board and still permit the player to concentrate his attention on the game board where it belongs.

More particularly, therefore, the invention relates to an improved form of bumper contact spring which includes a lamp to give an indication whenever a ball bumps the spring.

The main object of the invention is to provide an improved bumper contact spring structure for the purposes stated.

Another object is to provide an illuminated bumper contact spring ball rolling game obstacle.

Still another object is to provide such a bumper spring including an electric lamp operable every time a ball bumps the spring.

Another object is to locate these lamps for the bumpers in a manner not obstructing the game board.

Another object is to locate the lamp for each bumper on the vertical axis of the spring, either within the spring or above it.

A further object is to provide means on the game board itself to indicate when and what bumper is hit by a ball.

Other important objects, such as creating a pleasing eye effect by providing illuminated bumper springs; placing a lamp within the spring so that the coils will diffuse the light; and using different colors of lamps, also will be important to note as the disclosure is more fully made.

Briefly, these important objects can be achieved 10 by placing a lamp either within the spring and on the game board, or above the spring on the bumper support; in either event the lamp being included in the circuit with the bumper contacts so that when the latter are bumped and ball 15 closed the lamp will be turned on to designate to the player which bumper has been bumped.

In the drawing illustrating practicable forms of the invention:

Figure 1 is a general vertical sectional view 20 through the game board and an improved illuminated spring bumper type of ball obstacle;

Figure 2 is a top plan view of the bumper obstacle shown in Figure 1;

Figure 3 is a view similar to Figure 1, but 25 showing a modified form of the invention; and,

Figure 4 is a top plan view of the structure shown in Figure 3.

For both embodiments of the invention shown, the game cabinet structure is the same and comprises the usual cabinet 10 carrying a substantially horizontal game board or table 11, which may be slightly inclined from the horizontal in the well known manner to let balls roll gravitationally thereover. The board 11 is covered by 30 a glass panel 12.

The form of bumper obstacle shown in Figures 1 and 2 comprises an upright cylindrical support or sleeve 13 suitably anchored in the board 11 and extending thereabove, as shown. Surrounding the support 13 and resting on the board or table 11 is a spacer sleeve 14 for supporting at its upper end a washer disk 15 serving to lock a coil or cylindrical helical spring 16 in place under a cap 17, the upper edge of the support 13 being 40 swaged over the cap 17 as shown at 18. This coil spring is thus pendants supported and hangs downwardly concentrically around the support 14, with the lower coil of the spring spaced above the table 11, but having a vertically depending 45 leg extension 19.

This leg 19 extends down centrally into a carbon conductor ferrule 20 disposed in a conductor sleeve 21 embedded in the table 11 by means of a bore formed in the latter. An electrical wire

for a circuit 22 is connected to the sleeve 21, said circuit including a source of energy 23 from whence another lead 24 goes up the hollow support 13 for electrical connection to the terminal 5 of the socket for an electric lamp bulb 25 screw threaded into the support 13, as shown. Because the support 13 is also in the circuit it follows the spring 16 is likewise. Consequently the spring leg 19 represents one contact and the ferrule 20, 10 21 the other, for completing the circuit 22, 24. When the circuit is completed as the result of a ball rolling on the table 11 bumping against and laterally deflecting the spring 16, these contacts engage momentarily to close the circuit and light 15 the lamp 25 which is carried by the support 13 on its axis and above the spring 16. A solenoid, or other electromagnetic device 26 may be included in the circuit to be energized every time the contacts close, said device 26 being useful in operating some auxiliary means such as a score register, 20 as will be readily understood.

In Figures 3 and 4 a modification is shown in which the upright spring support is formed as a conductor bracket 27 passed through the board 25 or table 11 and secured at its under side as by screws 28, the upper end of the bracket carrying a cap 29 held in place by a screw 30. The cap carries the cylindrical helical spring 31 having the leg 32 passed down into the ferrule 20 and 30 sleeve 21 as was used in Figure 1. On the vertical axis of the spring 31 the table 11 carries a socket 33 for a lamp bulb 34. The socket includes a terminal 35 held by a conductor plate 36. The circuit 22 previously described is duplicated in this modification, and includes the solenoid 26, battery 28 and wire 24. The wire 21 connects to the contact 21, 22, and the wire 24 goes to the socket 33 for the lamp from whence current goes into support 27 and spring 31. In 40 this form the bulb 34 is concentrically disposed within the spring 31 so that the coils serve to diffuse the light onto the table in a pleasing manner. The support 27 is off-center relative to the axis of the spring. When the contacts 32, 45 28 close as the result of a ball deflecting the spring, the circuit is closed to light the lamp 34 and operate the device 26 in an obvious manner.

The manner of use and operation of the improved illuminated bumpers will now be clear. 50 By using different colored lamps a pleasing light-up effect can be produced.

It will now be apparent that the structures provided achieve all of the desirable objects for the invention heretofore recited. As many of 55 the improved bumpers may be used on a single table as is desired. One or both types may be used on the same table, if desired.

It is the intention to cover all changes and modifications of the examples disclosed which do 60 not in material respects constitute departures from the spirit and scope of the invention as hereinafter claimed.

What is claimed:

1. For a ball rolling game having a table over 65 which a ball is rollable and a cylindrical helical spring carried thereabove about an upright axis and forming one side of a contact switch, a contact carried on the board and forming the other side of the contact switch, said spring and contact being normally gapped apart in an electrical circuit closable when the ball rolling on the table 70 bumps and deflects the spring to engage it with said contact, an electric lamp included in the circuit and rigidly positioned on the axis of the 75 spring, said lamp being lighted when the circuit

is closed and being of less size than the diameter of the spring, whereby the spring protects the lamp from being engaged by a ball when the latter bumps the spring.

2. For a ball rolling game having a table over 5 which a ball is rollable and a cylindrical helical spring carried thereabove about an upright axis and forming one side of a contact switch, a contact carried on the board and forming the other side of the contact switch, said spring and contact being normally gapped apart in an electrical circuit closable when the ball rolling on the table 10 bumps and deflects the spring to engage it with said contact, an electric lamp included in the circuit and rigidly positioned on the axis of the 15 spring and over the spring, said lamp being lighted when the circuit is closed and being of less size than the diameter of the spring, whereby the spring protects the lamp from being engaged by a ball when the latter bumps the spring. 20

3. For a ball rolling game having a table over 25 which a ball is rollable and a cylindrical helical spring carried thereabove about an upright axis and forming one side of a contact switch, a contact carried on the board and forming the other side of the contact switch, said spring and contact being normally gapped apart in an electrical circuit closable when the ball rolling on the table 30 bumps and deflects the spring to engage it with said contact, an electric lamp included in the 35 circuit and rigidly positioned on the axis of the spring and within the same, said lamp being lighted when the circuit is closed and the coils of the spring diffusing the light from the lamp and the lamp being of less size than the diameter of the spring, whereby the spring protects the lamp from being engaged by a ball when the latter bumps the spring.

4. For a game comprising a table over which 40 a ball is rollable, a hollow upright support carried on the table, an electric lamp carried by the support, a cylindrical helical spring carried by the support and forming one side of a contact switch for a normally open electric circuit included in the game in which circuit the spring and lamp 45 are included, said spring embracing the support, and a contact forming the other side of said switch and operatively associated with the spring and supported by the table whereby a ball rolling on the table may bump and deflect the spring 50 for engagement of a portion thereof with the contact to close the circuit and light the lamp.

5. For a game comprising a table over which a ball is rollable, an upright support carried on the table, a vertical cylindrical helical spring 55 contact carried by the support above the table and forming one side of a contact switch for a normally open circuit included in the game and in which circuit the spring contact is disposed, said circuit including another contact forming the other side of the contact switch and carried by the table, the two contacts being proximately positioned in cooperative relation whereby they may engage and close the circuit when a ball 60 rolling on the table bumps and deflects the spring contact, and a lamp disposed rigidly on the table and in the said circuit to be lighted, said spring surrounding the lamp to protect it from the ball. 65

6. For a game comprising a table over which a ball is rollable, an upright support carried on 70 the table, a vertical cylindrical helical spring contact carried by the support above the table and forming one side of a contact switch for a normally open circuit included in the game and in which circuit the spring contact is disposed, 75

said circuit including another contact forming the other side of the contact switch and carried by the table, the two contacts being proximately positioned in cooperative relation whereby they may engage and close the circuit when a ball rolling on the table bumps and deflects the spring contact, and a lamp carried on the table and

disposed in the circuit to be lighted, the lamp surrounded by the spring to be protected from the ball thereby, the lamp further being rigidly disposed on the vertical axis of the spring and the support being located to one side of the lamp and said axis. 5
